G. W. MILLER

COMBINATION TOOL

Filed June 2, 1923

Patented June 30, 1925.

UNITED STATES PATENT OFFICE.

GEORGE W. MILLER, OF WAYNESVILLE, NORTH CAROLINA.

COMBINATION TOOL.

Application filed June 2, 1923. Serial No. 642,989.

To all whom it may concern:

Be it known that GEORGE W. MILLER, a citizen of the United States of America, residing at Waynesville, in the county of Haywood and State of North Carolina, has invented new and useful Improvements in Combination Tools, of which the following is a specification.

The object of the invention is to provide in one tool, essentially all the elements necessary to the use of a carpenter in laying off work of various kinds and to make the construction simple so that the device may be cheaply and quickly manufactured.

With this object in view the invention consists in a construction and combination of parts of which a preferred embodiment is shown in the accompanying drawings but which does not define the limits of the invention.

Figure 1 is a side elevational view of the invention with the parts in the extended position.

Figure 2 is a similar view with the parts in the collapsed position and the front face removed.

Figure 3 is a section on the line 3-3 of Figure 2.

Figure 4 is a section on the line 4-4 of Figure 1.

Figure 5 is a section on the line 5-5 of Figure 1.

The invention is designed for making various linear measurements and to this end the stock or body portion, which consists of the spaced housings 1 and 2 defining an intervening slot carries in the section 1 the elements of a rule which consist of the telescoping sections 3 which, when in collapsed position, are all housed within the section 1 and which, when extended, are prevented from separation by lugs 3 formed at the end of one section and engaging shoulders 4 in the extremity of the section in which it telescopes. The shoulders and lugs will obviously prevent extension of the section beyond the desired point and the several sections are suitably graduated for conventional linear measurements.

The housing 2 carries the calipers of which the legs 5 slide through guide eyes 6 formed in the end wall of the housing 2, the legs of the calipers having pivotal connections 7 with a slide 8 movable longitudinally in the housing and engaged by a

clamping screw 9 the shank of which passes through a longitudinal slot 10 formed in the front wall of the housing. Obviously when the clamping screw is loose it may be used as a handle to advance or withdraw the slide toward and from the end wall of the housing and thus cause the legs of the calipers to protrude, the extent of their separation being determined by the position of the slide in the housing. Obviously its position nearer the end wall through which the legs project will result in a wider separation of the legs than a position farther back from the end of said wall. When the desired separation of the legs has been effected by the proper position of the slide in the housing, the simple tightening of the clamping screw secures the slide in place and thus retains the seating of the calipers, the clamping screw engaging the outer face of the housing and the slide being drawn into firm frictional contact with the inner face.

The slot defined by the spacing of the two housings is designed to receive the blade 11 which is pivotally mounted on a shank of the clamping screw 12 passing loosely through one housing and threadingly engaging the other, the shank of the screw spanning the slot between the two housings. The blade may be swung to any position between that of perpendicularity to the stock or into folded position when it is disposed for its full length in the slot, the clamping screw 12 maintaining any desired position of the blade relative to the stock. The device can then be made to function as a square or bevel, depending on the position of the blade with respect to the stock.

The two housings are secured together and held in spaced relation by a tubular housing 13 adapted for the reception of a lead pencil, said tubular housing being provided with a clamping device for securing the pencil 14 in place therein, the clamping device consisting of an eccentric 15 pivotally mounted between ears 16 and provided with a shank 17 by which it may be readily turned. When the shank is in a position parallel with the housing, the eccentric effects a firm bearing on the pencil and secures it in position in its housing. Swinging the shank back withdraws the eccentric from contact with the pencil and permits its ready removal.

To provide for the use of the device in marking off a line parallel with the edge of the board, a slide 18 is mounted on the blade 11, engaging a lateral bead 19 on the blade and being provided with a clamping screw 20 by which it may be secured in fixed position on the blade, being capable of sliding movement along the blade when the clamping screw is loose. The housing 13 besides serving as an element in which the pencil may be retained when not in use, also serves as a means for holding the pencil at the time of marking off a parallel line as above described. In such a case the point of the pencil is advanced beyond that edge of the blade having the bead and the slide 18 is set the desired distance from the pencil point, this slide acting as a guide to follow the edge of the board while the device is being moved along the same, the pencil

the while drawing a line a fixed distance from the edge.

Having described the invention, what is claimed as new and useful is:—

A device for the purpose indicated comprising a stock provided with a longitudinal slot in one edge portion, a blade pivotally connected with the stock at one end thereof and capable of any position between that of perpendicularity to the stock and folded position within the slot, a slide mounted on the blade, and a pencil holder carried by the stock on the edge opposite the slot, means being provided for holding the pencil with the point advanced beyond the edge of the blade when the latter is perpendicular to the slot. 25 30 35

In testimony whereof he affixes his signature.

GEORGE W. MILLER.
